WASHER

Nadia A. Ovsey, Los Angeles, Calif.

Application July 24, 1933, Serial No. 681,896

2 Claims. (Cl. 68—15)

This invention relates to improvements in washing machines of the agitator type, whereby two washing operations may be conducted at the same time in separate bodies of liquid. Heretofore, washing machines were constructed with but a single tank adapted to receive the washing fluid and garments or fabrics to be washed. Ordinarily, it is highly desirable that different types of fabrics or garments be separately washed. For example, delicate undergarments are ordinarily not washed in the presence of heavier, badly soiled garments or fabrics. Colored goods are preferably not washed in the presence of table linen, etc. As a result, a washing machine of the usual type is operated over a prolonged period of time, the washing being conducted in batches.

The present invention is particularly directed to an arrangement of elements whereby an ordinary type of washing machine may be converted into one in which two distinct types of garments or fabrics may be washed simultaneously but not in contact with one another. In this manner, a single driving unit is caused to effectively conduct two washing operations, thereby increasing the capacity of the washer. More specifically stated, the invention is directed toward an annular container adapted to be positioned in the upper portion of the main washing tank and above the normal fluid level in the main washing tank, in conjunction with agitators or arms operatively connected to the normal agitating shaft or drive whereby garments or fabrics in both the main tank and in the auxiliary annular container may be washed.

An object of this invention, therefore, is to disclose and provide an arrangement of elements whereby two types of garments or fabrics may be simultaneously washed without coming in contact with each other.

A further object is to disclose and provide a device adapted to convert the usual type of washing machine into one in which two types of fabrics or garments may be simultaneously washed in separate bodies of washing fluid.

These and other objects, uses, advantages and modifications of the invention will become apparent to those skilled in the art from the following description, it being understood that the invention is not limited to the specific form of the device illustrated and described hereinabove but includes all such modifications and changes as come within the scope of this invention.

The accompanying drawing illustrates the invention.

Figure 1 is a plan view of the top of Fig. 2 showing the invention and omitting the washing machine lid.

Fig. 2 is a front elevation of a washing machine partly in section showing the invention therein as may be applied and with the lid shown in place.

Fig. 3 is an elevational detail view of the agitator.

Fig. 4 is a bottom plan detail view of the container.

Fig. 5 is a plan view of Fig. 6 showing a modified form of a container that rotates with the agitator shaft.

Fig. 6 is a view analogous to Fig. 2 showing in section the form shown in Fig. 5.

Fig. 7 is a fragmental detail view partly in section showing how the device may rest upon a rim of a washing machine of another construction.

Referring to the drawing, the washing machine is generally indicated at A and includes the main tank 1 suitably supported upon the legs 2. Within the tank 1 there is positioned an upright shaft or driving member 6. Means for driving said shaft are not shown but are generally positioned below the tank 1. The shaft 6 may be provided with arms or agitators 7 suitably attached to said shaft, the arms or agitators 7 being positioned in the lower portion of the tank 1 so that the garments or fabrics placed into the washing solution 8 may be agitated and washed in said solution.

The upper edge of the tank 1 may be provided with inwardly extending lip or flange 5. Supported upon such flange by an outwardly extending flange 4 is an annular container 3 provided with a concentric inner wall portion 9 having an outwardly extending lip 10. The container 3 is therefore concentric with respect to the tank 1 and surrounds the outward extension of shaft 6, the weight of the container resting upon the inwardly extending flange 5 of the tank 1. The container 3 may be of any suitable size but preferably is of sufficient depth so that when supported upon the inwardly extending flange 5 of the tank 1, the bottom of the container 3 is slightly above the normal level of the fluid 8 in the tank 1.

A suitable agitator, generally indicated at 11 and provided with downwardly extending arms 12, is removably attached to the upper end of the driven shaft 6 as by means of a bushing or sleeve 13. In order to prevent splashing, the washing machine may be provided with a lid 16 having a suitable edging strip, such as the rubber strip 17. It will be obvious from the descrip-

tion given hereinabove that one type of garment or fabric may be placed into the washing solution 8 in the tank 1, the annular container 3 then lowered over the upward end of shaft 6 and suspended upon the flange 5 of the tank 1, additional washing fluid introduced into the container 3, a different type of garment or fabric placed into such washing solution, the agitator arms 11 slipped into operative engagement with the upper end of shaft 6, and the machine placed into operation whereby the two types of garments can be simultaneously washed without coming into contact with one another. In this manner the garments of persons afflicted with contagious diseases may be separately washed without the necessity of subsequently sterilizing all of the garments or fabrics washed.

A modified form of the invention is illustrated in Figs. 5 and 6. As there shown, the annular container 18 may be provided with an inwardly extending lip, the inner wall section being closed at the top, as indicated at 14, and having paddles or blades 19 extending radially from said inner wall and integral therewith. The entire container 18 can thus be slipped upon the upper end of the shaft 6 and be supported thereon by the end portion 14 of the container. Partial oscillatory rotation of the shaft 6 will thereby move the entire container 18.

As shown in Fig. 7, the annular container 3 may be provided with an outwardly extending flange 20 adapted to rest upon the upper edge of the tank 1.

These and other modifications will be obvious to those skilled in the art. All such changes and modifications as come within the scope of the appended claims are embraced thereby.

I claim:

1. In a washing machine, the combination of a tank, an upright driven shaft in said tank, an agitator carried by said shaft in the lower portion of said tank, a removable imperforate annular container positioned in the upper portion 10 of said tank, said container being provided with a tubular axial bore surrounding said shaft, and an agitator arm removably attached to said driven shaft and extending into said annular container for agitating liquid in said container 15 whereby garments may be washed simultaneously in said tank and container in separate bodies of washing fluid.

2. In a washing machine, the combination of a tank, an upright driven shaft in said tank, an 20 agitator positioned in the lower portion of said tank and operatively connected to said shaft, a removable imperforate annular container supported by the upper edge of said tank and extending thereto, and an agitating member 25 provided with downwardly extending arms removably attached to said shaft, said arms extending into said annular container for agitating liquid in said container, whereby garments may be washed simultaneously in said tank and said 30 container in separate bodies of washing fluid.

NADIA A. OVSEY.
